RAILWAY CAR

George E. Reed, Frontenac, and Dallas W. Rollins, St. Charles, Mo., assignors to ACF Industries, Incorporated, New York, N.Y., a corporation of New Jersey

Filed Feb. 1, 1965, Ser. No. 83,645

Term of patent 14 years

(Cl. D66—1)

FIG. 1.

FIG. 2

FIG. 3.

FIG. 4

FIGURE 1 is a perspective view of a railway car showing our new design;

FIGURE 2 is a side elevational view of the railway car shown in FIGURE 1;

FIGURE 3 is an end elevational view of the railway car shown in FIGURES 1 and 2; and

FIGURE 4 is a cross-sectional view of the railway car shown in FIGURE 1.

The side and end of the railway car not shown in the drawings are substantially the same as those shown.

The dominant features of our design reside in the shape of the railway car body shown in full lines.

We claim:

The ornamental design for a railway car, as shown and described.
